SHEET MATERIAL DISPLAY DEVICE

John Austin Taylor, Elmhurst, N. Y., assignor to
Heinz Art Service, New York, N. Y.

Application May 4, 1946, Serial No. 667,455

3 Claims. (Cl. 40—126)

1

This invention relates to new and useful improvements in display forms, and has particular reference to a collapsible cardboard structure primarily intended for use in store windows, on counters, and in similar places.

It is a general object of my invention to provide an improved display device composed entirely of cardboard or equivalent inexpensive sheet material which can be quickly and easily adjusted at will from a collapsed, substantially flat condition, to an operative set-up condition.

A more particular object of my invention is to provide a device whose structural nature and surface embellishment is of such a character that when the device is set up it will simulate one or more articles or other commercial items. The invention is primarily applicable to the depiction of bottles whose simulation is capable of accomplishment by forwardly expanding or bulging a normally flat element of sheet material. Of course other articles than bottles may be equally well simulated.

Further and more specific objects, features, and advantages will more clearly appear from the detailed description hereinafter set forth especially when taken in connection with the accompanying drawings which illustrate a present preferred form which the invention may assume and which form part of the description.

Briefly and in the most general terms the invention comprises a main back and supporting sheet which folds along a vertical center line to extend forward in a diverging angle to form two side walls. The central portion of this main sheet on each side of the center line and intermediate the top and bottom thereof is bent forward to form intermediate walls forwardly converging. Out of this central portion is stamped a tab which extends from the outer edge of one intermediate wall horizontally to a slit formed in the outer edge of the other and the end of the tab is formed with a tongue to engage said slit and hold the intermediate walls in their angular relation. The edges of the side walls are cut back at two points to simulate separate tiers for purposes which will appear later.

At the bottom of the main sheet and between the side walls there extends a flat sheet or strip which can be folded in a zig-zag manner and which is connected by tongue and slit connections to the side walls at its ends and by similar means at its intermediate portion to one of the intermediate walls.

To the various sloping surfaces thus formed by the side walls, the intermediate walls, and

2

the sloping surfaces of the bracing member may be connected by stapling but preferably by adhesive a series of tiered rows of article-representing forms which may be shaped and decorated to represent bottles. In this latter case these particular sheets may be bulged to simulate the curvature of bottles.

By merely disconnecting the tongue and slit connections which hold the intermediate walls in angular position, the device may be folded flat and to completely disassemble the device it is then necessary merely to disconnect the tongue and slit connections between the bracing member and the side and intermediate walls above described.

The lower tier of bottle-representing forms are connected to the intermediate bracing member and the side walls; the middle tier of forms are connected to the side walls and the intermediate walls; and the top form is connected to the side walls and the intermediate walls; and the top form is connected to the side walls alone.

The present preferred form which the invention may assume is illustrated in the drawings, of which

Fig. 1 is a front elevation of the form in operative position;

Fig. 2 is a side elevation thereof;

Fig. 3 is a plan view thereof;

Fig. 4 is a rear elevation of the assembled form;

Fig. 5 is a view of the main blank laid flat;

Fig. 6 is a flat view of the intermediate lower bracing and form supporting member; and

Fig. 7 is a flat view of one of the article-representing forms.

In the specific form chosen to illustrate the invention the device when in opened operative position represents a series of bottles having three in the lower tier, two in the middle tier, and one in the top tier or row. These bottle-representing forms are sheets 10 of cardboard shaped in profile to represent bottles and, suitably decorated to thus simulate bottles although the decoration is not herein shown. They are stamped from flat sheets but when connected in position are bulged out to represent the curve of the bottles. These forms have foldable lateral edges 11 whereby they can be, in one form of the device, adhesively connected to the various walls of the main support.

The frame on which and to which these forms are connected comprises a main sheet or blank 12 foldable along a vertical center line 13 to form side walls 14 and 15 to extend forward in a divergent angular relation as shown in Fig. 3. This sheet 12 is cut back at 16 and 17 along its edges

for reasons which will be obvious as the description unfolds. The central portion of the sheet 12 intermediate at top and bottom wall is also folded forward to form intermediate walls 18 and 19 as shown in Fig. 3, which extend forward in a converging angular relation. A lock tab 20 is cut out of the sheet 12 and extends from the outer side 21 of the intermediate wall 18 toward the outer side of the intermediate wall 19 where there is cut a slit 22 into which a tongue 23 on the end of tab 20 engages to lock the parts in their proper relation. To engage the tongue and the slit it is necessary to push the walls 18 and 19 into their angular relation shown in Fig. 3 and to fold the sheet 12 forwardly as shown in the same figure. This engagement therefore is the main lock to hold the form in its operative opened position.

Along the bottom of the sheet 12 there are disposed three slits 24, one in the middle of each side wall and one at the line of fold 13. An intermediate bracing and supporting member 25 is shown in Fig. 6 and is made up of four sections 27 foldably connected with lock tongues 28 at the ends and in the middle thereof. This member 25 is folded in a zig-zag manner and disposed as shown in Fig. 3 and connected at its ends with the slits 24 in the side walls and at its middle with the slit 24 in the center line of fold at the apex of the angle formed by the intermediate walls 18 and 19. Thus the member 25 is held in position and also assists in holding the side walls 14 and 15 firmly. The sections 27 also act as supports for the lower tier of bottle-representing forms 10 as shown in Fig. 3 to which sections these forms 10 are glued, as shown, by tabs 11.

In operation, the sheet 12 and the forms 10 and the bracing member 25 are flat as shown in Figs. 5, 7, and 6 respectively. The sheet is folded with the side walls forwardly extending and with the center portion pushed also forward to form the intermediate walls at a middle level of the sheet. Then the tab 20 can be locked in the manner described to hold the form in this position. Then the bracing member 25 is folded zig-zag and connected at its ends and the middle as described along the lower portion of the sheet between the side walls. The forms 10 are then glued to the respective walls thus disposed to support them. When the device is to be packed for storage or shipment all that need be done is to release the tab 20 and also the member 25 whereupon the whole device can be pressed flat.

While the invention has been described in detail and with respect to a present preferred form which the invention may assume, it is not to be limited to such details and form since many changes and modifications may be made in the device without departing from the spirit and scope of the invention in its broadest aspects. Hence it is desired to cover any and all forms and

modifications of the invention which may come within the language or scope of any one or more of the appended claims.

What I claim as my invention is:

- 5 1. A display device which comprises a sheet foldable along a vertical central line at a divergent angle to form side walls, a central portion thereof bendable forward at a convergent angle to form intermediate walls, tongue and slit means on the sheet to hold the portions in their folded position, a bracing member foldable in a zig-zag manner and disposed along the lower portion of the sheet extending between the side walls thereof and tongue and slit connections for connecting the ends of the bracing member to the side walls and its middle to one of the intermediate walls.
- 10 2. A display device which comprises a sheet foldable along a vertical central line at a divergent angle to form side walls, a central portion thereof between the top and bottom bendable forward at a convergent angle to form intermediate walls, a tab formed from the sheet and extending from the outer side of one intermediate wall toward the outer side of the other intermediate wall which has a slit therein and a tongue on the tab to engage the slit to hold the parts in their folded position.
- 15 3. A display device which comprises a sheet foldable along a central vertical portion at a divergent angle to form side walls, a central portion thereof between the top and bottom of the sheet bendable forward at a convergent angle to form intermediate walls, a tab formed from the sheet and extending from the outer side of one intermediate wall and toward the outer side of the other intermediate wall which has a slit therein, a tongue on the tab to engage the slit to hold the parts in their folded position, a bracing member foldable in a zig-zag manner and disposed along the lower portion of the sheet extending between the side walls thereof and tongue and slit connections for connecting the ends of the bracing member to the side walls and its middle to one of the intermediate walls, and article representing forms bent in a curve and glued at their side edges to the various side, intermediate and bracing member walls at various levels to simulate a pyramid or group of articles on display.
